VEHICLE DOOR LATCH

Holden W. Rightmyer, Toledo, Ohio, assignor to
 The American Swiss Company, Toledo, Ohio, a
 corporation of Ohio

Application November 26, 1937, Serial No. 176,571

7 Claims. (Cl. 292—164)

This invention relates to vehicle door latches and is particularly concerned with an automobile door latch having an inside operated remote control handle which, when actuated in non-bolt retracting direction, disconnects the outside handle or renders the latter ineffective, affording operation thereof in the usual manner but without imparting retracting movement to the latch bolt.

Other objects reside in details of construction, arrangement and operation as will hereinafter appear and for purposes of illustration but not of limitation, an embodiment of the invention is shown on the accompanying drawings in which:

Figure 1 is an elevation of a portion of a door panel with the outside handle in place;

Figure 2 is a transverse sectional view through a portion of a door showing the door latch mechanism and the outside operated handle therefor;

Figure 3 is a sectional view substantially on the line 3—3 of Figure 2 showing the door latch mechanism, the parts being disposed in operative position enabling retraction of the latch bolt from the inside or outside of the door;

Figure 4 is a view somewhat similar to Figure 3 but showing the inside operated remote control advanced to render the outside operated handle ineffective; and

Figure 5 is a fragmentary view of the face of the case plate flange showing the manner in which the outside operated handle is pivotally mounted.

The illustrated embodiment of the invention comprises a door having an outside panel 10 and an inside panel 11 connected at the outer or forward edge by the usual plate 12. The outside door panel 10 is formed with a recess 13, the side edges of which taper outwardly therefrom. Disposed in the recess is the outside operated handle 14, the end portions of which are disposed normally well within the socket or recess 13 to provide in effect the flush type handle. Provided in the recess 13 is an opening 15 through which a portion 16 of the handle of substantially S shape extends, the inner end of the handle being secured to an actuating arm 17 by a screw 18a (Figure 5).

The arm 17 is formed with a pair of outwardly extending flanges 18 which fit respectively between a pair of outwardly extending flanges 19 integral with a flange 20 forming a part of a case plate 21. Extending through the flanges 18 and 19 is a pin 22 which provides a pivotal connection between the actuating arm 17 and the flange 20 of the case plate. The case plate 21 is suitably fixed in any well-known manner to the

door panel 11 and slideable through an opening formed in the case plate flange 20 and the door panel 12 is the nose 23 of a latch bolt. The latch bolt nose 23 is fixed to a bolt plate 24 which is slideable over the case plate 21, the rear end portion thereof having inwardly extending tongues 25 which ride in elongate slots 26 formed in the case plate for guiding the movement of the bolt. A bridge member 27 having a flat spring member 28 also assists in guiding the movement of the bolt. The bolt is urged to latching position by a spiral spring 29 having one end secured to the case plate 21 and the opposite end abutting the rear face of the bolt nose 23.

The latch bolt is retracted from the inside of the door by a slide 30 which is disposed beneath the inner end of the bolt plate 24 and is also guided in its longitudinal sliding movements by the bridge member 27 and by the tongues 25. On the outer end of the slide is a T head 31 disposed in advance of the tongues 25 so that by movement of the slide 30 to the right (Figure 3), the T head 31 engages the tongues 25 and further movement in that direction retracts the latch bolt against the force of the spring 29. A link 32 is pivoted at one end to the inner end of the slide 30 and extends to a suitable remote control handle mechanism (not shown), the latter being well-known to those skilled in this art and detailed description thereof is not considered necessary.

Continuing further with the description of the outside operated retracting means, the inner end of the actuating arm 17 engages an upwardly extending flange 33 on the outer end of a plate 34 which is guided for longitudinal sliding movements on the case plate 21 by a pin and slot connection 35. Connected to the plate 34 and extending inwardly therefrom is a rod 36 on which is mounted a coil spring 37 the outer end of which abuts against a plate 34 and the inner end of which abuts against an ear 38 struck from the case plate 21, the rod 36 passing through an aperture in the ear 38. The plate 34 is formed with a shoulder 39 which is engageable with a transversely movable slide 40 which is carried by the bolt plate 24 and is guided for transverse sliding movement thereover by pairs of ears 41 struck from the bolt plate. The slide 40 is secured to the bolt plate by a rivet 42 passing through an elongate slot 43 in the slide and disposed between the head of the rivet 42 and the slide is a plate spring member 44 having a flange 45 engaging the bolt plate 24 and oppositely disposed tongues 46, the upper one of which is engageable

in a slot 47 the lower one of which is engageable in a slot 48 when the slide is moved into one position or the other thereby to hold the slide in its adjusted position. When the slide is in its lowermost position as shown in Figure 3, the lowermost part is disposed directly in rear of the abutment or shoulder 39 on the plate 34 thereby enabling retraction of the latch bolt from the outside of the door by movement of the handle 14 to the dotted line position indicated in Figure 2. When the slide 40 is moved to the position shown on Figure 4, it will be apparent that the outside operated door handle 14 is rendered ineffective because the lower portion of the slide is moved away from the shoulder 39. When the slide is in the latter position, the handle 14 can be manipulated in the usual manner but without imparting retraction movement to the latch bolt, the plate 34 sliding along the case plate 21 but free from operative connection to the latch bolt, the coil spring 37 returning the slide to its normal position and retaining the handle 14 in the desired position.

The slide 40 is moved into its operative position in rear of the shoulder 39 from the outside by a key-operated device as will hereinafter appear. The head 31 of the retracting slide 30 engages a pivoted sector member 49 which is pivoted at 50 to the case plate 21. The opposite end 30 of the arm 49 engages a flange 51 on the upper end of the slide 40. By moving the retracting slide 30 ahead to the position shown in Figure 4, the arm 49 is rocked in a clockwise direction moving the slide 40 to its uppermost position and enabling the lower spring tongue 46 to snap into the slot 48.

Integral with the slide 40 and extending outwardly or forwardly and upwardly therefrom is an extension arm 52, the free end of which is engaged by an eccentric cam 53. The cam 53 can be swung from the position shown on Figure 4 to the position shown on Figure 3 thereby to render the outside operated door handle 14 operative. Thus, by movement of the retracting slide 30 the outside operated handle 14 may be rendered inoperative when the door is closed and to open the door, the cam 53 is swung downwardly to the position shown on Figure 3 enabling the latch bolt to be retracted by manipulation of the handle 14.

Means are provided for automatically rendering the outside handle 14 operative upon slamming of the door or retracting movement of the slide 30 from the inside of the door. For this purpose, a spring 54 has its ends anchored to the case plate 21 and is formed with a downwardly and rearwardly inclined portion 55 which is engaged by the slide 40 when the latch bolt is moved rearwardly or in a retracting direction and in riding along the inclined surface 55 the slide 40 is moved downwardly to the position shown on Figure 3 in which the upper spring tongue 46 snaps into the slot 47 for yieldingly holding the slide in such position.

It is to be understood that numerous changes in details of construction, arrangement and operation may be effected without departing from the spirit of the invention especially as defined in the appended claims.

What I claim is:

1. In a vehicle door latch the combination of a spring-tensioned latch bolt, outside operated retracting means for said latch bolt, a member carried by said latch bolt and movable relatively thereto for establishing an operative connection

with said outside retracting means, inside retracting means having lost motion relative to said latch bolt, means operative upon said lost motion for actuating said member bodily away from operative connection with said outside retracting means, and means independent of said inside retracting means for automatically moving said member to operative position during retraction of said latch bolt away from latching position.

2. A vehicle door latch comprising a spring-tensioned latch bolt, a slide movable transversely of said latch bolt and carried thereby, an outside operated retractor for said latch including a rectilinearly movable member engaging said slide, an inside operated retractor having lost motion relative to said latch bolt in non-bolt retracting direction, means operative in response to said lost motion for actuating said slide out of the path of movement of said rectilinearly movable member, and means independent of said inside retractor for automatically returning said slide to normal position in operative relation to said rectilinearly movable member during retraction of said latch bolt away from latching position.

3. A vehicle door latch comprising a spring tensioned rectilinearly slidable latch bolt, inside operated retracting means for said latch bolt including a slide actuating member engageable with said latch bolt and having lost motion in a non-bolt retracting direction, a slide carried by said latch bolt and movable transversely thereof, a pivoted member disposed between said actuating member and said slide and so arranged that movement of said actuating member in a non-bolt retracting direction rocks said pivoted member which in turn imparts movement to said slide away from normal position, and an outside operated retracting member engageable with said slide for retracting said latch bolt when the slide is in its normal position.

4. A vehicle door latch comprising a spring tensioned rectilinearly slidable latch bolt, inside operated retracting means for said latch bolt including a slide actuating member engageable with said latch bolt and having lost motion in a non-bolt retracting direction, a slide carried by said latch bolt and movable transversely thereof, a pivoted member disposed between said actuating member and said slide and so arranged that movement of said actuating member in a non-bolt retracting direction rocks said pivoted member which in turn imparts movement to said slide away from normal position, and stationary means disposed in the path of movement of said slide when the latter is out of normal position for causing movement thereof to normal position during the retraction of the latch bolt.

5. A vehicle door latch comprising a spring tensioned rectilinearly slidable latch bolt, inside operated retracting means for said latch bolt including a slide actuating member engageable with said latch bolt and having lost motion in a non-bolt retracting direction, a slide carried by said latch bolt and movable transversely thereof, a pivoted member disposed between said actuating member and said slide and so arranged that movement of said actuating member in a non-bolt retracting direction rocks said pivoted member which in turn imparts movement to said slide away from normal position, yieldable means for moving said slide to normal position during the retraction of the latch bolt, an extension on

said slide, and rotatable cam means engaging said extension for actuating said slide.

6. In a vehicle door latch, the combination of a spring tensioned latch bolt, outside operated retracting means for said latch bolt, a member carried by said latch bolt and movable relatively thereto for establishing an operative connection with said outside retracting means, inside retracting means having lost motion relative to 10 said latch bolt, means operative upon said lost motion for actuating said member bodily away from operative connection with said outside retracting means, separate means for holding said member in either inoperative or operative position, and means independent of said inside retracting means for automatically moving said member to operative position during retraction of 15 said latch bolt away from latching position.

7. A vehicle door latch comprising a spring tensioned rectilinearly slidable latch bolt, inside operated retracting means for said latch bolt, including a slidable actuating member engageable with said latch bolt and having lost motion in 5 a non-bolt retracting direction, outside operated retracting means for said bolt, a slide carried by said latch bolt and movable transversely thereof to and from operative relation to said outside means, and a separate member disposed between said actuating member and said slide and so arranged that movement of said actuating member in a non-bolt retracting direction moves said member which in turn imparts movement to said slide away from operative position relative to said outside means. 10 15
